UNITED STATES PATENT OFFICE

HENRY LE PUL, OF HEMPSTEAD, NEW YORK

COMBINATION FUEL PUMP AND FUEL INJECTOR FOR DIESEL ENGINES

Application filed October 6, 1930. Serial No. 486,532.

This invention relates to new and useful improvements in a combination fuel pump and fuel injector for Diesel engines, and relates particularly to the subject matter of my copending application, Serial No. 407,802 filed on November 18th, 1929.

In the copending application, it is proposed to provide a body member comprising a top section with a reduced cylindrical lower end and a central bore, an intermediate tubular section engaged on and extending below said reduced lower end, and an outer section encasing said intermediate section and fixedly connected with the inner section and formed with a closed bottom having an axial fuel discharge consisting of a small conical recess connecting with a coaxial passage, a plunger slidably mounted in the bore of said top body section and formed at the bottom with an enlarged head slidably mounted in the portion of the intermediate body section below the top body section and normally slightly spaced from the lower end of the inner body section for forming an annular fuel compression chamber, a blow off valve in said plunger head interposed in a passage between said fuel compression and the side of a small conical projection engaging for closing the passage and the fuel discharge and projecting from the bottom of said plunger head.

The operation according to the above construction consists in the plunger moving upwards to compress the fuel within the fuel chamber, and the blow off valve being set so that the pressure reaches a very high one, such as 5000 pounds per square inch, before fuel discharges through the passage and strikes against the conical recess and continues through the fuel discharge passage. The upward motion of the plunger produces a new chamber beneath it so that air from the cylinder of the Diesel engine, which is normally at a pressure of 500 pounds, may move through the fuel discharge passage and fill up the newly formed chamber. This chamber is quite small so as to support but a small percentage of the combustion qualities of the fuel. The passage of air from the engine cylinder into this newly formed chamber opposes to a very small degree the discharge

of fuel through the passage into the cylinder of the engine.

It is an object of this invention to provide means for reducing the size of the newly formed chamber to a minimum so as to reduce the retarding effect of the incoming air upon the discharging of the fuel, and also to reduce the combustion of the fuel within the newly formed chamber.

It is particularly proposed to provide a projection with vertical sides from the bottom of the plunger head and terminating in said conical projection, and slidably engaging within a portion of the bottom of said outer body section so as to limit the size of the passage chamber beneath the plunger head formed by the upward motion of the plunger to force fuel from the fuel compression chamber through the passages and the fuel discharge in said closed bottom.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:—

Fig. 1 is a vertical sectional view of a combination pump and injector constructed according to this invention, certain parts being shown in elevation.

Fig. 2 is a horizontal sectional view taken on the line 2—2 of Fig. 1.

Fig. 3 is a horizontal sectional view taken on the line 3—3 of Fig. 1, and

Fig. 4 is an enlarged detailed view of a portion of Fig. 1 showing all parts in section.

The combination fuel pump and fuel injector for Diesel engines consists of a plunger 10 for operation by the cam shaft of an engine and working in a body member 11 formed with an inlet passage 12 connecting with a fuel compression chamber 13, said plunger 10 being arranged upon its injecting stroke to pass said inlet passage 12 and entrap and compress the fuel within the chamber 13, and a blow off valve 14 connected with fuel chamber 13 for directing the discharge of

fuel under pressure into a cylinder of the said engine. The body 11 is made from several sections and only one of said sections being provided with the said inlet passage 12. This section is adjustable in position for determining the size of the fuel compression chamber 13 for feeding regulated quantities of fuel to the engine for throttle control.

The said body member 11 consists of an inner section 15, an intermediate section 16 and an outer section 17. The inner section 15 has a central bore 18 extending its complete length, and also has a bottom reduced portion 19, a central flange portion 20 and a top externally threaded portion 21.

The said intermediate section 16 has a central bore 22 extending its full length and is slidably mounted on the bottom reduced portion 19 of the inner section 15. The intermediate section 16 extends materially below the bottom end of the inner section 15. A packing gland 23 is threadedly engaged in the intermediate section and packing 24 is clamped beneath the gland and between the inner and intermediate sections for providing a fuel tight connection. The intermediate section 16 is formed with lateral rack teeth 25, and with a transverse aperture constituting the said inlet passage 12. This aperture is positioned a small distance below the bottom end of the inner section 15.

The said outer section 17 is provided with a central bore 26 extending through its top end to a small distance from the bottom end, and is adapted for attachment upon the cylinder of an engine. The outer section terminates at the top in a pair of lugs 27 which are engaged against the bottom side of the said central flange 20. Screws 28 engage through the flange and into the lugs for holding the outer section in fixed relation to the inner section. A lateral passage 29 in the outer section 17 aligns with the passage 12 in the central section. A pair of lugs 30 project from one side of the outer section 17 and support a pin 31 carrying a rocker arm 32 with teeth at one end meshing with the rack teeth 25. A control lever 33 is attached upon the pin 31 so that upon motion of the lever, the rocker arm moves for raising or lowering the intermediate body section 16. A valve seat 34 is formed in the outer body section 17 at the bottom of the bore 26 and connects with a passage 35 for discharging into a cylinder of the engine.

The said plunger 10 has a finished central portion 36 and an enlarged bottom head 37. The central portion 36 is slidably engaged through the bore of the inner section 15 and is formed with a plurality of packing grooves 38 adapted to be filled with oil for forming an oil packing. A packing gland 39 threadedly engages in the inner section and forces packing material 40 tightly between the inner

section and the central portion of the plunger rod for forming a liquid tight joint.

The enlarged head portion 37 of the plunger is disposed within the intermediate body section 16 and is a slide fit in its central bore. The top of the enlarged head portion 37 is slightly spaced from the bottom end of the inner body section 15 providing a space which constitutes the fuel chamber 13. A transverse fuel aperture 45 is formed within the plunger 10 and communicates with the fuel chamber 13. A longitudinal fuel passage 46 connects with the transverse passage 45 and communicates with a bottom bore 47 formed in the bottom end of the plunger 10. This bore is so arranged as to provide a valve seat 48.

A bottom plug 49 threadedly engages on the bottom end of the enlarged head 37 of the plunger and is formed with a bottom projection 50 constituting a valve head for acting against the said valve seat 34 in the outer body section 17. Fuel passage grooves 51 extend from the valve head 50 to a bore 52 within the bottom plug 49 and which aligns with the bore 47 in the plunger. A valve head 53 is slidably engaged within the bores 47 and 52. An expansion spring 54 normally urges the valve head against the seat 48.

A filler rod 55 is attached upon the valve head and passes through the central opening of the spring 54 so as to fill up all excess spaces for reducing the compass of fuel collecting in the bore 47 and 52. The valve head 53 is slightly shorter than the overall length of the bores 47 and 52 so as to provide a slight space 56 permitting a slight longitudinal movement of the valve. As shown in Fig. 4 the valve is of hollow construction so as to house the expansion spring 54. A spiral fuel passage groove 57 is formed upon the periphery of the valve 53 so as to permit the passage of fuel from the longitudinal passage 46 to the passages 51 and hence if the valve 50 is open to the passage 35.

The bottom projection 50 has vertical sides and a conical free end. The vertical sides engage within a bore in the bottom of the outer body section 17, and the conical end engages said valve seat 34. The diameter of the upper portion of the conical projection 50 is greater than the diameter of the valve bore 47 so that the fuel passages 51 may not break out from the sides of the projection and terminate in the conical portion a slight distance from the apex so that when the plunger head is in its lowered position, the projection 50 acts as a valve and closes the passage through the passage 35 and the passages 51. The diameter of the projection 50 should be very small, in fact as small as it is possible to make it, relative to the diameter of the plug 49. The height of the vertical sides of the projection 50 should be greater than the stroke of the plunger, that is,

greater than the height of the compression chamber 13 so that when the plunger is in its highest position, the vertical sides of the projection 50 will not disengage from the bore in the body section 17.

A spring housing 58 is threadedly engaged upon the threaded portion 21 of the inner body section. A collar 59 is fixed upon the plunger 10 and an expansion spring 60 acts between the collar and the spring housing 58 for normally urging the plunger downwards. Lugs 61 project from the spring housing 58 and support a pin 62 carrying a rocker arm 63 engaging the bottom side of the collar 59. A lever 64 is fixed upon the pin 62 and is intended for connection with the cam shaft of the engine.

In operation of the device, a supply of fuel is fed into the passage 29. This fuel enters the fuel chamber 13 through the passage 12. At the proper moment, as determined by the cam shaft of the engine, the lever 64 is moved so that the rocker arm 63 lifts the plunger 10. As the plunger moves upwards, the head portion 37 forces back all excess fuel from the fuel chamber 13 until it passes the passage 12 and then compresses the entrapped fuel within the chamber 13. Continued upward motion of the plunger soon raises the pressure of the entrapped fuel to a predetermined amount as determined by the strength of the spring 54.

As this pressure is reached, the valve 53 automatically moves downwards and the fuel is then free to enter the passage 46, continue along the spiral groove 57, continue along the passages 51 and finally discharge from the passage 35 into the cylinder of the engine. Obviously, this fuel is discharged at a high pressure which is necessary since the pressure within the cylinder of a Diesel engine during intake is about 500 pounds. It is very easy to raise a pressure of the inlet fuel to 5000 pounds or more with this arrangement.

As the plunger 10 moves upwards, a small chamber is formed beneath the conical projection 50 and the body section 17. The projection 50 moves upwards, but at all times maintains contact with the body section 17 so as to divide off this chamber from another chamber section which is formed to the bottom of the plug 49 and the body section 17.

As the plunger 10 moves upwards so as to compress the fuel within the fuel chamber 3 to a high pressure so that the valve 14 pens to discharge the fuel under pressure through the passage 35, air from the cylinder will tend to enter into the newly formed chamber, but since this chamber is so very small this air will be of a negligible quantity. The air will not hinder the discharge of the fuel through the passages 51, then against the inclined sides 34 and through the passage 35, in that the fuel is under a very much greater pressure than the air which tends to

travel inwards. The small quantity of air which may enter the newly formed chamber beneath projection 50 is so small that it can support but a very small percentage of the combustible qualities of the discharged fuel, so that the greater percentage of the fuel will burn within the cylinder of the Diesel engine.

The quantity of fuel injected into the engine at each operation of the device may be controlled by manipulation of the lever 33. Motion of the lever moves the rocker arm 32 and consequently raises or lowers the intermediate body section 16. As the body section is raised, the position of the fuel passage 12 is changed relative to the bottom and of the inner body section 15. Consequently the size of the portion of the fuel chamber which holds the entrapped fuel is varied.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit or the scope of the appended claim.

Having thus described my invention, what I claim as new, and desire to secure by United States Letters Patent is:—

In a combination fuel pump and fuel injector for Diesel engines, a body member comprising a top section with a reduced cylindrical lower end and a central bore, an intermediate tubular section engaged on and extending below said reduced lower end, and an outer section encasing said intermediate section and fixedly connected with the top section and formed with a closed bottom having an axial fuel discharge consisting of a small cylindrical recess with a conical pointed end connecting with a coaxial passage, a plunger slidably mounted in the bore of said top body section and formed at the bottom with an enlarged head slidably mounted in the portion of the intermediate body section below the top body section and normally slightly spaced from the lower end of the top body section for forming an annular fuel compression chamber, a small cylindrical element with a conical point projecting from the bottom of said plunger head and engaging in said cylindrical recess for closing the fuel discharge and of sufficient length so as not to disengage from the recess upon complete upward motion of said plunger, a blow off valve interposed in a passage between said fuel compression chamber and the side of said conical point, and said cylindrical element slidably engaging the cylindrical recess in the bottom of said outer body section so as to limit the size of the chamber beneath the plunger head formed by upward motion.
